US0D1027526S

(12) **United States Design Patent** (10) **Patent No.:** **US D1,027,526 S**
(45) **Date of Patent:** **** May 21, 2024**

(54) **ATTACHABLE SUPPORT STRUCTURE**

(71) Applicant: **Burrow, Inc.**, New York, NY (US)

(72) Inventor: **Evan Clabots**, Brooklyn, NY (US)

(73) Assignee: **Burrow, Inc.**, New York, NY (US)

(**) Term: **15 Years**

(21) Appl. No.: **29/783,552**

(22) Filed: **May 13, 2021**

(51) LOC (14) Cl. **06-06**

(52) U.S. Cl.

USPC **D6/717**

CLAIM

The ornamental design for an attachable support structure, as shown and described.

DESCRIPTION

FIG. 1 is a perspective view of the attachable support structure.

FIG. 2 is a top plan view of the attachable support structure.

FIG. 3 is a bottom plan view thereof.

FIG. 4 is a front elevational view thereof.

FIG. 5 is a rear elevational view thereof.

FIG. 6 is a left side elevational view thereof; and,

FIG. 7 is a right side elevational view thereof.

The broken lines indicate portions of the attachable support structure that form no part of the claimed design.

1 Claim, 4 Drawing Sheets
